MAN'S UNDERGARMENT

Weldon O. Denbo, Port Arthur, Tex.

Application August 31, 1956, Serial No. 607,416

5 Claims. (Cl. 2—224)

This invention relates to wearing apparel, and more particularly to an improved man's undergarment.

A main object of the invention is to provide a novel and improved undergarment which is simple in construction, which is comfortable to wear, and which provides a substantial degree of body support while permitting free movement of the portions of the body adjacent thereto.

A further object of the invention is to provide an improved man's undergarment which is easy to put on and to take off, which is neat in appearance, which provides firm support of the portions of the body received therein while at the same time being readily yieldable so as to allow free movement of said body portions, being easy to launder, and requiring a minimum number of stitching operations in the fabrication thereof.

A still further object of the invention is to provide an improved man's undergarment of the type having a waistband and which also serves as a supporter, supporting the portions of the body received therein substantially directly from said waistband.

Further objects and advantages of the invention will become apparent from the following description and claims, and from the accompanying drawings, wherein:

Figure 1 is a front elevational view with a part broken away, of an improved man's undergarment constructed in accordance with the present invention.

Figure 2 is a front elevational view of the undergarment of Figure 1 with the front flap thereof in open position.

Figure 3 is a perspective view showing the manner in which the undergarment of Figures 1 and 2 acts as a yieldable support for portions of the body received therein.

Figure 4 is an enlarged transverse vertical cross sectional view taken on line 4—4 of Figure 3.

Figure 5 is a perspective view, similar to Figure 3, but showing the front flap of the undergarment in open position.

Referring to the drawings, the improved undergarment is generally designated at 11 and comprises a tubular body of yieldable fabric material, shown at 12, for example, rubberized fabric material or suitable knit fabric material having elastic qualities, the body 12 comprising an upper back portion of relatively large width, including the respective side wing portions 13, 13. Secured to the top margin of the upper back portion of body 12 is a waist band 14. The back portion of body 12 tapers downwardly to define a relatively narrow crotch portion 15 at its lower end, extending from the midportion of the bottom margin of the body 12.

The respective side portions of the body 12 merge with a front flap 16, defined by inverting the front portion of the body, which is joined to the lower portions of the sides of the main body 12, as by the joining sections 17, 17, the front flap 16 being preferably of substantial width, so that it may overlap the end portions of the waist band 14 when in its elevated position, for example, the

2

position shown in Figures 1 and 3. The end portions of the waist band 14 are provided with spaced snap fastener elements 18, and the flap 16 is provided at its margin with a waist band section 19 to the end portions of which are secured cooperating snap fastener elements 20, 20, as shown in Figure 2, adapted to lockingly interengage with selected snap fastener elements 18, whereby the flap 16 may be secured in its closed position, shown in Figures 1 and 3.

10 The bottom edge of the front flap member 16, as viewed in Figure 4, is connected to the opposite edge of the crotch portion 15 by an elastic band 21 of substantial width, as shown in Figures 1 and 4, the band 21 being of any suitable rubberized webbing material having substantial strength and being readily yieldable to conform with the contours of the wearer's body.

If so desired, the band 21 may be omitted, and the crotch portion 15 may be extended and may be fastened to the bottom edge of the flap 16, so that the entire garment may be made of a single piece of material suitably formed and shaped, and provided with the main waist band 14 and the flap waist band segment 19.

As will be readily understood, the flap 16 may be readily opened, as required, and when closed, defines a supporting pouch or sack which conforms to the contours of the portions of the body received therein and which is readily yieldable so that it is comfortable to wear.

As above mentioned, the body 12 may be made of a single piece of flexible fabric material, either of rubberized fibers, or of suitably knit material. Alternatively, the main body 12 of the garment may be made up of sections suitably fastened together, as by stitching or the like, in order to provide economic utilization of material.

The various edges of the garment may be provided with suitable hems or piping, as shown at 25 and 26 in Figure 1, to protect the edges of the material, and to prevent irritation of the body from contact with such edges.

It will be noted that in its inverted position, illustrated in Figure 1, the front flap 16 tapers upwardly in width from its juncture with the lower side portions of the ends of the back of the yieldable body 12, whereby the supporting pouch or receptacle is defined when the snap fastener elements 20 are secured to the selected mating snap fastener elements 18. Obviously, any suitable fastener elements may be employed in place of the snap fastener elements 18, 20, for example, buttons and button holes, or the like.

If so desired, the garment may be constructed with a single waistband, namely, by combining the elements 19 and 14 in a unitary, continuous elastic waistband, or alternatively, the fasteners 18, 20 may be eliminated and the ends of waistband section 19 may be stitched to the end portions of waistband 14.

While a specific embodiment of an improved man's undergarment has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a man's undergarment, a tubular body of yieldable fabric material comprising an upper back portion of relatively large width, respective side wing portions merging with said back portion, a waist band on the top margin of said upper portion and side wing portions, a relatively narrow crotch portion extending from the midportion of the bottom margin of said back portion, a front flap defined by inverting the front portion of said body, said inverted front portion extending upwardly and being formed and arranged to overlap the margins of said side wing portions, said inverted front portion being substan-

tially smaller in width than said back portion, said inverted front portion tapering upwardly in width, whereby its top margin is substantially shorter than its bottom margin, an elastic band secured between said crotch portion and the bottom edge of said inverted front portion, and interengaging fasteners on the top corner portions of said inverted front portion and the end portions of said waist band.

2. In a man's undergarment, a continuous tubular body of yieldable fabric material comprising an upper back portion of relatively large width, respective side wing portions merging with said back portion, a waist band on the top margin of said upper portion and side wing portions, a relatively narrow crotch portion extending from the mid portion of the bottom margin of said back portion, a front flap defined by inverting the front portion of said body, said inverted front portion extending upwardly and being formed and arranged to overlap the margins of said side wing portions, said inverted front portion being substantially smaller in width than said back portion, said inverted front portion tapering upwardly in width, whereby its top margin is substantially shorter than its bottom margin, an elastic band secured between said crotch portion and the bottom edge of said inverted front portion, and interengaging fasteners on the top corner portions of said inverted front portion and the end portions of said waist band, said inverted front portion merging at its lower side portions with the lower side portions of said back portion.

3. In a man's undergarment, a tubular body of yieldable fabric material comprising an upper back portion of relatively large width, respective side wing portions merging with said back portion, a waist band on the top margin of said upper portion and side wing portions, a relatively narrow crotch portion extending from the mid portion of the bottom margin of said back portion, a front flap defined by inverting the front portion of said body, said inverted front portion extending upwardly and being formed and arranged to overlap the margins of said side wing portions, said inverted front portion being substantially smaller in width than said back portion, said inverted front portion tapering upwardly in width, whereby its top margin is substantially shorter than its bottom margin, an elastic band secured between said crotch portion and the bottom edge of said inverted front portion, and means connecting the top corner portions of said inverted front portion to said waist band.

4. In a man's undergarment, a continuous tubular body of yieldable fabric material comprising an upper back portion of relatively large width, respective side wing portions merging with said back portion, a waist band on the top margin of said upper portion and side wing portions, an elastic, relatively narrow elastic crotch band secured to and extending from the midportion of the bottom margin of said back portion, a front flap defined by inverting the front portion of said body, the lower edge of said inverted front portion being secured to the forward end of said band and extending upwardly and being formed and arranged to overlap the margins of said side wing portions, said inverted front portion being substantially smaller in width than said back portion, said inverted front portion tapering upwardly in width, whereby its top margin is substantially shorter than its bottom margin, a waist band segment secured to the top margin of said inverted front portion, and interengaging fasteners on the end portions of said waist band segment and the end portions of said waist band, said inverted front portion merging at its lower side portions with the lower side portions of said back portion.
5. In a man's undergarment, a tubular body of yieldable fabric material comprising an upper back portion, respective side wing portions merging with said back portion, a waist band on the top margin of said upper portion and side wing portions, a relatively narrow crotch portion extending from the midportion of the bottom margin of said back portion, a front flap defined by inverting the front portion of said body, said inverted front portion extending upwardly and being formed and arranged to overlap the margins of said side wing portions, said inverted front portion being substantially smaller in width than said back portion, means connecting said crotch portion and the bottom edge of said inverted front portion, and means detachably connecting the top corner portions of said inverted front portion to said waist band.
